UNITED STATES PATENT OFFICE.

JOHN C. BANNISTER, OF KEWANEE, ILLINOIS.

METHOD OF AND APPARATUS FOR MAKING MOLDS AND CORES.

1,034,336.

Specification of Letters Patent.

Patented July 30, 1912.

Application filed January 11, 1912. Serial No. 670,631.

To all whom it may concern:

Be it known that I, JOHN C. BANNISTER, a citizen of the United States, residing at Kewanee, in the county of Henry and State of Illinois, have invented a new and useful Method of and Apparatus for Making Molds and Cores, of which the following is a specification.

My invention relates to making green sand cores and half-molds which are later assembled in making a complete mold, and employed to manufacture metal castings; and the invention more particularly relates to making such cores or half-molds or molds in multiple within core boxes and flask sections in readiness for the flask to be booked or assembled and the cores transferred thereto preparatory to the later casting operation.

It has heretofore been proposed to make half-molds by delivering the sand into the flask section in which the mold is being formed through the medium of fluid pressure such as compressed air. In such apparatus, a quantity of sand is placed within the sand boot and is then forced or caused to pass downwardly through openings or holes located in the bottom of the sand boot into the flask section or sections, the best known form of such apparatus being that covered by the Hewlett Patents Nos. 808,367, 819,883, and 823,580. With such apparatus, the sand which is placed in bulk in the sand boot, becomes packed and compressed thereby to some extent by the action of the fluid pressure used to force or propel the sand therefrom. The compressed air also frequently cuts channels or passages through the body of sand through which the air travels and when formed such passages or channels lessen the flow of sand into the mold or half-mold to an extent which appreciably adds to the time required to fill the mold with sand. The formation of such channels or passages in the body of the sand within the boot renders it necessary to interrupt the mold forming operations in order to permit the sand within the boot to be stirred or shaken up so as to destroy the openings or channels.

One object of my invention is to provide a novel method of handling and delivering the sand from the sand boot into the flask

sections in making green sand cores and half-molds. 55

Another object of the invention is to provide molding apparatus having improved means whereby the method of forming green sand molds and cores forming part of this invention is effected and the delays experienced in the operation of the apparatus heretofore in use are prevented and overcome. 60

Still further objects of the invention will be disclosed as the invention is more fully 65 described hereinafter.

Referring to the accompanying drawings forming part of this specification, Figure 1 is a side elevation showing one form of apparatus constructed and arranged in accordance with my invention and adapted for use in carrying out the method of making cores, half-molds and molds forming part of the invention. Fig. 2 is an end elevation of the apparatus shown in Fig. 1. 70 Fig. 3 is a side elevation showing a modified form of apparatus also adapted for use in carrying out the method forming part of this invention. Fig. 4 is an end elevation of the apparatus shown in Fig. 3. Fig. 5 is 75 a detail sectional elevation of the apparatus of Figs. 1 and 2 on a larger scale, showing the arrangement of the flask sections and core boxes, as applied to the sand boot. Fig. 6 is a detail longitudinal section of the apparatus shown in Figs. 3 and 4, on an enlarged scale showing the core box and blow plugs as arranged in accordance with this invention. Fig. 7 is a plan of the multiple 80 core box shown as applied for use in Figs. 5 and 6. Fig. 8 is a plan showing the half pattern as made in being applied to the apparatus shown in Figs. 1, 2, and 5 in making a multiple half-mold. 85

In the drawings, in which pipe fittings 95 known as T's are shown being made, and referring to Figs. 1, 2 and 5 the numeral 2 designates a sand boot having legs or feet 3 by which the apparatus is mounted upon a suitable foundation or like support. Brackets 4 are provided on the sides of the sand boot 2 to which the lower ends of the vertically extending standards or uprights 5 are secured, and mounted on the upper ends of the uprights 5 is a support 6 on which the vertical fluid pressure cylinder 7 is mount- 100 105

ed. The lower end of this cylinder is provided with a stuffing box and gland 8 through which the piston rod 9 of the piston 10 in the cylinder 7 extends. The lower 5 end of the piston rod 9 is attached to the vertically movable top platen 11 of the apparatus and the side edges of the platen 11 are provided with grooves or notches 12 which engage with the vertical standards 5 10 and act as guides when the platen is moved vertically. The sand boot 2 is divided by the partitions 13 and 14 into three separate compartments 15, 16 and 17, in which the molding sand is placed in bulk. Opening 15 into the compartments 15, 16 and 17 through the bottom of the sand boot 2 are the supply pipes 18, 19 and 20 which deliver the compressed air or other fluid pressure to the compartments used in delivering or expelling the molding sand from the compartments of the sand boot 2 into the half-molds and into the core-boxes during the mold and the core forming operations. The upper 20 end of the sand boot 2 is open, normally being covered by the bottom platen or table 21. The top platen 11 is arranged to be lifted from the boot 2 to permit the supply of sand used in the molding operations to be put into the compartments 15, 16, and 17 of 25 the sand boot and also to allow the interior of the sand boot to be examined. The tongue or projection 22 on the lower face of the vertically movable platen projects downwardly into the rabbet or groove 23 in 30 the top edge of the sand boot 2 so as to accurately position the platen or table 21 on the sand boot when lowered after each successive platen lifting operation. A gasket formed of a suitable material may be and 35 preferably is used in forming and maintaining a tight joint between the faces of the top edge of the boot 2 and platen 21. To facilitate lifting of the bottom platen or table 21, bolts 24 are provided being located in 40 registering holes in the top platen or table 11 and bottom platen 21, these bolts being of a length permitting the top platen 11 to have a limited vertical movement without any corresponding movement of the bottom 45 platen 21 while affording means for lifting the bottom platen when desired by means of the fluid pressure cylinder 7 which is operatively connected by the piston rod 9 to the top platen. Hook bolts 25 extending 50 through other holes in the top platen 11 have hooks 25^a on their lower ends which are arranged to engage with lugs 26 on the ends of the bottom section 27 of the half-core boxes 27 and 28. The hook bolts turn 55 in the holes to bring the hooks 25^a into engagement with the lugs 26 so that when the top platen 11 is raised by the piston 10 in the fluid pressure cylinder 7 the core-box 60 will be lifted to clear the upper ends of the blow plugs 29 and 30 which project up-

wardly above the upper surface of the blow plug plate 31 and permit the core-box to be removed from beneath the lifted top platen 11. A pad or seat 32 is provided on the lower surface of the top platen 11 to engage 70 with and hold the core-box in position upon the blow plug plate 31. Recesses 33 which are located on opposite sides of the pad 32 are formed in the under surface of the top platen 11 in which the pattern plates 34, 34 75 are seated so as to accurately position the series of half patterns 35, or, when the mold for a single casting is being made, the single half pattern then used, on the molding apparatus, in the relative location necessary 80 to cause the half molds to register when the flask sections 36, 36 are "booked" or assembled in readiness for the later casting operation. Bolts or other suitable fastenings are used to detachably secure the pattern plates 34 in the seating recesses 33, which are located in the top platen 11. The bottom platen 21 has a rectangular opening therethrough and a rabbet in the top surface of the platen 21 provides a recess in 90 which the blow plug plate 31 is seated and positioned on the platen 21 with the lower end of the blow plugs opening into the middle compartment 16 of the sand boot 2. Openings or holes 37 are provided in the bottom platen 21 which serve to connect the compartments 15 and 17 of the boot 2 with the interior of the flask sections 36 and through which the molding sand passes 95 into the flask when the flask sections are placed on the platen 21 in position for the mold forming operations and the top platen 11 has been lowered to bring the half patterns 35 into position within the flask sections. A shelf, or a shelf formed by arms 100 38 extends outwardly from one side of the sand boot 2 upon which the molded flask section 36 and the core-boxes 27 and 28 are placed when removed from between the platens 11 and 21 in position to be handled 105 manually or by means of an air hoist in being carried to the casting floor of the foundry.

It is to be noted that with the apparatus described and shown in Figs. 1, 2 and 5 both of the flask sections later forming the core and drag molds as well as the cores therefor are simultaneously formed in readiness to be assembled preparatory to the casting operation in which the series of 110 castings are formed.

In the construction of Figs. 3, 4 and 6, apparatus is shown which is particularly intended for use in carrying out the steps of my improved method in manufacturing green sand cores either singly or in multiple. The cores when formed are removed in the core-boxes and later transferred from the core-boxes into the sand molds prepared to receive the cores. In this appa- 115 120 125 130

ratus the sand boot 2' is provided with legs or feet 3', and has a supply pipe 19' connecting the single compartment 16' of the sand boot, through its bottom, with the 5 source of compressed air or other fluid pressure used in forcing the sand therefrom into the core box formed of the half core boxes 27' and 28'. A bottom platen or table 21' is mounted on the open upper end of the 10 sand boot and the rectangular opening 21^a in this platen 21' is rabbeted so as to position the blow plug plates 31' seated therein during the core forming operations. Brackets 4' on the ends of the boot 2' provide 15 supports for the uprights or standards 5' which in turn secure the cylinder support 6' on their upper ends and the cylinder 7' carried thereby in the same manner as has been heretofore described. The cylinder 7, 20 which extends vertically lengthwise, has a piston 10 on one end of a piston rod 9' which projects downwardly through the stuffing box and gland 8' on the lower end of the cylinder. The outer end of the piston 25 rod 9' is connected to the top platen or table 11', as before described, and this top platen 11' has grooves or notches 12' in its marginal edges which engage with the uprights 5' and form guides for the platen 11' when 30 the platen is raised and lowered during the core forming operations. The top and bottom platens are connected by bolts 24' to lift the lower platen 21' from the boot 2' and afford means for placing sand in quantities within the sand boot in preparation 35 for the core forming operations. Hook bolts 25' are also provided to lift the core boxes sufficiently to clear the blow plugs 29' and 30' extending upwardly into the core 40 box through the openings provided for that purpose in the bottom section 29' of the two half boxes 27', 28', forming the complete core box. A shelf 38', or arms forming a shelf, is also provided on the side of this sand boot 45 2' as before. Suitable valves are located on the supply pipes 18, 19, 20, leading to the compartments of the sand boot 2 and pipe 19' leading to the sand boot 2' and a four way valve is employed in the pipes 50 connecting the lifting cylinder 7 or 7' with a fluid pressure supply to regulate and control the entrance of fluid pressure to the sand boot 2 or 2' and to the lifting cylinder 7 or 7'. 55 In using the apparatus of Figs. 1, 2 and 5 for carrying out the steps of my improved method, to simultaneously form a series of half-molds and the cores therefor in multiple, the compartments 15, 16 and 17 of the sand boot 2 are provided with a supply of 60 molding sand, the operating cylinder 7 being caused to lift the bottom platen 21 so as to provide an opening in the sand boot through which the sand is placed in the 65 compartments thereof. The middle com-

partment 16 which supplies the sand used in making the cores may contain sand differing in composition from that in the other two compartments in the sand boot when found necessary or desirable.

The valve controlling the operation of the lifting cylinder is then manipulated to lower the platen 21 into position on top of the sand boot 2. The flask sections 36 in which the half-molds are formed are then positioned as shown in these figures, and a core box is placed in position on the blow plug plate 31, the blow plugs 29 and 30 extending upwardly through the registering openings in the bottom half 27 of the core box, so that the side outlets 29^a and 30^a in the blow plugs 29 and 30 as well as in the plugs 29', 30' adjacent to the closed upper ends of the blow plugs, are positioned within the core boxes opposite the open ends of 35 the core forming cavities within the core boxes. The top platen 11 is then lowered into engagement with the top surfaces of the flask sections 36 and the top half 28 of the core box by a proper manipulation of 90 the valve for the lifting cylinder 7, and, if necessary, fluid pressure is maintained on the upper end of the piston in the cylinder 7 in order to hold the flask sections and core boxes in place between the platens 11 95 and 21. This movement of the platen 11 also brings the half patterns 35 supported thereon into position within the flask sections to form the cavities in the half-molds. Air or other fluid pressure used in delivering sand from the sand boot into the core box and the flask sections, is then admitted to the compartments 15, 16, and 17 of the sand boot, by opening the valves controlling the fluid pressure supply pipes 18, 19 and 100 20. The fluid pressure, as it enters the compartments of the sand boot 2, rises therein and passing through the body of sand, enters through the holes 37 into the flask sections 36 and through the blow plugs 29 105 and 30 into the core box, and emerges therefrom through the joints between the platens and the edges of the flask sections and vents in the flask sections, and through the joints between the half boxes 27, 28 of the core 110 box. Care is taken to avoid making these joints so tight as to prevent escape of the fluid pressure at the necessary rate and if necessary, added means may be provided to facilitate such escape from the flask sections into the atmosphere. The fluid pressure passing from the sand boot will carry or force the sand to travel therewith and become deposited in the flask sections and core box, the sand gradually filling the flask sections and cavities in the core box and becoming equally packed therein in such manner as to be uniformly dense throughout the body of the so-formed half-molds 115 and cores. The fluid pressure in passing 120 through the joints between the platens and the edges of the flask sections and vents in the flask sections, and through the joints between the half boxes 27, 28 of the core box. Care is taken to avoid making these joints so tight as to prevent escape of the fluid pressure at the necessary rate and if necessary, added means may be provided to facilitate such escape from the flask sections into the atmosphere. The fluid pressure passing from the sand boot will carry or force the sand to travel therewith and become deposited in the flask sections and core box, the sand gradually filling the flask sections and cavities in the core box and becoming equally packed therein in such manner as to be uniformly dense throughout the body of the so-formed half-molds and cores. The fluid pressure in passing 125 through the joints between the platens and the edges of the flask sections and vents in the flask sections, and through the joints between the half boxes 27, 28 of the core box. Care is taken to avoid making these joints so tight as to prevent escape of the fluid pressure at the necessary rate and if necessary, added means may be provided to facilitate such escape from the flask sections into the atmosphere. The fluid pressure passing from the sand boot will carry or force the sand to travel therewith and become deposited in the flask sections and core box, the sand gradually filling the flask sections and cavities in the core box and becoming equally packed therein in such manner as to be uniformly dense throughout the body of the so-formed half-molds and cores. The fluid pressure in passing 130

upwardly through the sand boot constantly stirs or agitates the body of sand contained therein, so as to entirely prevent the formation of passages or channels therein and the resulting retardation or interruptions of the mold and core forming operations. After the flask sections and the core box become filled with sand, fluid pressure is shut off from the sand boot 2. The cylinder 7 is then caused to lift the platen 11, thereby removing the half-molds 35 attached to the lower surface thereof from the flask sections and at the same time lifting the core box, by means of the hook bolts 25 which engage with the lugs 26 on the core box so as to clear the upper ends of the blow plugs 29 and 30. The flask sections 36 are then removed from between the then separated platens 11 and 21, and the core box is removed from the hooks 25^a on the bolts 25 from which the core box is now suspended. The flask sections and core box containing the formed cores and half-molds are then removed from the molding apparatus. The top half 28 of the core box is then lifted so as to uncover the series of multiple cores therein, and one flask section 36 is "rolled" or turned over and is placed on top of the bottom section 27 of the core box containing the cores. The flask sections and core box sections are provided with the usual complement of dowel pins and registering holes or openings so as to insure proper registration with each other of the series of half molds formed in each flask section and the cores in the core box. The half core box and half-mold placed thereon are then turned together so as to bring the bottom half of the core box uppermost. This half box is then removed, thereby uncovering the cores which are now accurately positioned in the half molds formed in the flask section. The second flask section is then placed in position on top of the other flask section and with this operation the complete mold, with the cores in position therein, is assembled, or, in the vernacular of the foundry, is "booked". The sprue or runner if not already formed in making the mold, is then formed and the mold vented in the usual manner, when the mold is in readiness for the casting operation, in which the molten metal is poured into the cavities of the mold and the castings thereby formed.

It will be readily seen by those skilled in the art that the above described apparatus and method can be employed to advantage in making a mold, or mold and core, later used in forming a single casting, instead of simultaneously forming the plurality of molds, as before described.

With the apparatus shown in Figs. 3, 4 and 6, the core forming operations are the same as hereinbefore described for making cores with the apparatus of Figs. 1, 2 and 5,

the difference being that cores alone are formed which are later carried to a place of use where they are transferred to a mold which has been formed independently of the core forming operations, and which may be either machine or hand molded.

The advantages of my invention will be apparent to those skilled in the art. The sand is placed within the sand boot in bulk and is then delivered into the flask sections and the core boxes as required. The sand is caused to become uniformly packed therein and form molds and cores of uniform density, the formation of defective molds and cores thereby being lessened and prevented to a large extent. By causing the sand to flow upwardly into the bottom of the flask sections, instead of as heretofore discharging the sand downwardly from the sand boot, packing of the sand in the sand boot so as to in effect lessen the capacity of the sand boot is effectually prevented, and the formation of passages or channels through the body of sand and leading to each of the outlet openings into the flasks and core box is avoided.

Modifications in the construction and arrangement of the parts may be made without departing from my invention. The apparatus may be employed for use in making a single mold or a single core instead of making molds or cores in multiple, as shown. A single half-mold may be made instead of simultaneously forming two half-molds and the cores, as illustrated in the drawings. The apparatus of Figs. 3, 4 and 6 may be employed in making half-molds instead of cores as shown, and other changes in the construction and arrangement of the apparatus may be made without departing from my invention as defined in the claims.

Modifications in the apparatus shown and the methods described herein for making cores and molds, are claimed in my co-pending applications, Serial No. 659,159, for method of and apparatus for making sand molds, filed November 8, 1911, and Serial No. 659,160, for method of and apparatus for making cores, filed November 8th, 1911.

I claim:

1. The method of making molds and cores which consists in placing a container in which the molds or cores are formed upon a sand boot, admitting fluid pressure to the sand boot to carry sand therefrom into the container, and causing the fluid pressure and sand to pass from the upper end of the sand boot into the container in forming the molds and cores.

2. The method of making molds and cores which consists in placing a container in which the molds or cores are formed upon a sand boot, supplying fluid pressure to the sand boot through the bottom thereof to carry sand from the boot into the container.

and thereby form the molds and cores within the container.

3. The method of making molds and cores which consists in placing the containers in which the molds and cores are formed upon the top of a sand boot, admitting fluid pressure to the sand boot through the bottom thereof to carry sand from the boot into the containers and thereby form the molds and cores within the containers.

4. The method of making sand molds which consists in placing a flask section upon a sand boot, placing a half pattern on top of said flask section to leave the imprint of the pattern in the sand mold formed in said flask section, and supplying fluid pressure to the sand boot to force sand from the boot into the flask section on top thereof and thereby form a mold within said flask section.

5. In apparatus for making sand molds and cores, a sand boot having openings in the upper end thereof through which sand is delivered to the flask sections in forming the molds, and means on said boot adapted to supply gaseous fluid pressure thereto and force the sand upwardly through said openings into the flask sections on top of said sand boot in forming the molds and cores.

6. In apparatus for making sand molds and cores, a sand boot having openings in the upper end thereof through which sand is delivered to the containers in which the molds and cores are formed, blow plugs in said openings arranged to project into the containers and having closed outer ends with a side outlet adjacent to the closed outer ends whereby the direction of flow of the sand passing therethrough is changed in emerging from the blow plug, and means on said boot adapted to supply gaseous fluid pressure thereto and force sand upwardly from the boot through the blow plugs into the flask sections in forming the molds and cores.

7. Apparatus for forming green sand molds and cores comprising a sand boot having a platen or table thereon arranged to support the flasks and core boxes in which the molds and cores are formed, means for supplying fluid pressure to the sand boot through the bottom thereof to propel sand therein upwardly out of the top end of the sand boot into the flasks and core boxes, and

means movable into and out of position for holding the flasks and core boxes in position on the platen during the mold and core forming operation.

8. Apparatus for forming green sand molds and cores comprising a sand boot having a platen or table thereon arranged to support the flasks and core boxes in which the molds and cores are formed, means for supplying fluid pressure to the sand boot through the bottom thereof to propel sand therein upwardly out of the top end of the sand boot into the flasks and core boxes, means movable into and out of position for holding the flasks and core boxes in position on the platen during the mold and core forming operation, and power means for actuating the holding means.

9. Apparatus for forming green sand molds and cores comprising a sand boot having a platen or table thereon arranged to support the flasks and core boxes in which the molds and cores are formed, means for supplying fluid pressure to the sand boot through the bottom thereof to propel sand therein upwardly out of the top end of the sand boot into the flasks and core boxes, means movable into and out of position for holding the flasks and core boxes in position on the platen during the mold and core forming operation, and power means for actuating the holding means, said holding means having half patterns removably secured on the lower face thereof, arranged to enter the upper ends of the flask sections and leave the imprint thereof in the sand forced into the flask from the sand boot.

10. In apparatus for making sand molds and cores, a sand boot having openings in the upper end thereof through which sand is delivered to the flask and core boxes placed thereon in forming the molds and cores, and means for supplying fluid pressure to said sand boot to lift and force the sand upwardly from the sand boot through said openings into the flask and core boxes whereby to form the molds and cores.

In testimony whereof, I have hereunto set my hand.

JOHN C. BANNISTER.
